UNITED STATES PATENT OFFICE.

EUGEN WACKER, OF STOCKTON, CALIFORNIA, ASSIGNOR TO PHIL LANDMANN, OF STOCKTON, CALIFORNIA, ALBERT ANCKER, OF TEHACHAPI, CALIFORNIA, AND M. DAVIDSON, OF STOCKTON, CALIFORNIA.

NUT-LOCK.

SPECIFICATION forming part of Letters Patent No. 766,782, dated August 2, 1904.

Application filed October 2, 1903. Serial No. 175,531. (No model.)

To all whom it may concern:

Be it known that I, EUGEN WACKER, a citizen of the United States, residing at Stockton, in the county of San Joaquin and State of California, have invented certain new and useful Improvements in Nut-Locks, of which the following is a specification.

My invention relates to improvements in nut-locks, the object of my invention being to provide a device of this character which shall be cheap and simple in construction, convenient in operation, and effective in its result.

My invention therefore resides in the novel construction, combination, and arrangement of parts for the above ends hereinafter fully specified, and particularly pointed out in the claim.

In the accompanying drawings, Figure 1 is a longitudinal section of a bolt having thereon a nut constructed in accordance with my invention, said section being taken to one side of the axis of said bolt. Fig. 2 is a cross-section of the bolt close to the inner face of the nut. Fig. 3 is a view similar to Fig. 2, showing the manner of releasing the lock to allow the nut to be unscrewed.

Referring to the drawings, 1 represents a bolt which differs in its construction in no respect from ordinary bolts. 2 represents the nut, in the inner face 3 of which is formed a locking-cavity 4, having a rounded end 5 for the reception of a key 6, which has a rounded end to rest in the rounded end of the cavity. The cavity flares slightly toward the center of the nut to permit a slight swing of said key therewithin. Said cavity does not, however, extend directly toward the center of the nut, but to one side thereof—namely, to the rear side—having regard to the movement of the nut when screwing up. The consequence is that when so screwing up the inner end of the key swings to the rear side of the cavity and rides upon the thread of the nut, offering no resistance to the forward or screwing-up movement of the nut; but it prevents any unscrewing due to vibration or other accidental cause, owing to the fact that upon a rearward movement of the nut upon the bolt the inner end of

the key catches or bites the thread of the bolt, and the deviation of the key from a direction 50 normal to the thread being slight the pressure caused by the engagement of the inner end of the key with the thread increases the biting action and effectually prevents the unscrewing of the nut.

In order to insure the engagement of the inner end of the key with the thread, the rear side of the cavity is formed with a transverse recess 7, in which is fitted a spring 8, which I have here shown of rubber, although it need 60 not necessarily be so; but a small coiled spring may be used. This insures the initial bite of the key on the thread necessary to positively prevent the accidental unscrewing of the nut.

To unscrew the nut when desired, there is 65 provided an unlocking-pin 9, which is passed into a groove or cavity 10, formed in the inner face of the nut, the groove at its inner end running into the locking-cavity 4. The inner end of the pin can thus be pressed against 70 said key, and by pressure applied to said pin the inner end of the key may be forced away from the thread, permitting the nut to be unscrewed. Said pin is provided with a notch 11, which when the pin is pressed fully in- 75 ward is engaged by a tooth 12, extending inward at the side of the entrance of the unlock- ing-groove. The engagement of said tooth with said notch holds the pin in its place, press- 80 ing the locking-key away from the bolt, and thus allows the nut to be more readily un- screwed.

Since the bolt is not changed in construction and the groove and cavity in the face of the nut can readily be stamped out when making 85 the nut and the locking and unlocking pin are small parts very easily made, the increased cost of construction is trifling, while at the same time there is provided an effective and convenient nut-lock.

I claim—

In a nut-lock, a nut having movably mounted therein a locking-key engaging the thread of the bolt slightly to the rear of the normal direction thereto, to bite said thread when un- 95 screwing the nut, said nut having a transverse

cavity to receive a pin to engage a key to hold it in its unlocking position and having a tooth 12 extending inward at the side of the entrance of the unlocking groove or cavity, said 5 tooth being adapted to engage a notch in said pin, substantially as described.

In witness whereof I have hereunto set my

hand in the presence of two subscribing witnesses.

EUGEN WACKER.
